EXERCISING DEVICE

Frank O'Neill, Jr., New York, N. Y.

Application September 12, 1934, Serial No. 743,691

17 Claims. (Cl. 272—69)

This invention relates to exercising devices of the treadmill type.

Special objects of the invention are to provide an exerciser of the type mentioned, which will be relatively simple and of light, compact design, foldable to occupy small space, adjustable to suit different individuals, quiet in use, thoroughly practical and inexpensive as to cost.

These and other desirable objects are attained by the novel features of construction, combinations and relations of parts hereinafter described, broadly claimed and illustrated in the accompanying drawings.

The drawings referred to show by way of example one of the practical embodiments of the invention, but it is to be understood that the structure may be modified and changed in various ways all within the intent and broad scope of the claims.

Fig. 1 is a side elevation showing the invention as in use.

Fig. 2 is a broken plan view illustrating the apparatus in its folded form.

Fig. 3 is an end view of the device.

Figs. 4 and 5 are enlarged broken sectional details as on lines 4—4 and 5—5 of Fig. 1.

Fig. 6 is a broken sectional view showing the supports folded under to lower the platform to horizontal position.

Fig. 7 is a cross-sectional detail as on line 7—7 of Fig. 1.

The base of the apparatus consists in the present disclosure of a single plate of sheet metal 10, reinforced and stiffened by the turned down edge flanges 11, braced together at the end and intermediate portions by the cross rods 12, 13, 14.

At the ends, between the down turned edge flanges, the top portion of the base is rolled downwardly and inwardly at 15, to form curved guides for the track surface, which is shown as an endless belt 16, travelling over the top and around these curved guides. This belt may be any suitable flexible fabric.

A special feature of the present invention is that the platform may be supported either in inclined or horizontal relation to suit different methods of exercise.

In Fig. 1, the base or platform is shown supported in the inclined position suitable for walking or running exercises, sustained so by the legs or supports 17. The latter are indicated as hingedly connected with the top at 18, so that they can be folded under as at Fig. 6 to then maintain the base in a substantially horizontal position.

Structurally the hinged supports may be sheet metal pieces flanged at the edges as at 19, in box form, to stiffen them and to provide the end and side bearing surfaces 20, 21. These bottom and side bearing surfaces may be faced with rubber or other suitable cushioning material such as shown at 22, and which may be in the form of continuous strips of facing material. The other side flanges 23 of the legs provide bearing faces to which the hinge leaves may be spot welded or otherwise suitably secured as indicated at 24. The companion leaves of these leg hinges may be spot welded or otherwise secured to the top plate as indicated at 25. The top flanges 26 of the legs also serve a special purpose, in that in the upright position they abut the underside of the top to solidly support the latter and to take part of the load off the hinges.

The opposite and what may ordinarily be the lower end of the platform is supported in the illustration by somewhat similar hinged feet 27, having flanges 28, faced with strips 30 of rubber or other suitable cushioning friction material.

Uprights 31 are provided for supporting a handle, hand grips, a belt, or the like, and these are combined in the present disclosure with the feet 27, the latter being shown as lower extensions of these uprights. The stay-rods 12, provide the pivotal mountings for these combined legs and uprights. A preferred arrangement of these parts is indicated in Fig. 4, where the stay-rod is shown as extending through bushings 33, secured in the side flanges 11, these bushings having washers 34 at the outside providing thrust bearings for the legs, which latter are held in position by cap nuts 35, screwed on the ends of the rod against washers 36.

To securely hold the uprights in the position of use, hinge braces 37 are provided pivotally connected at 38 and 39, with the uprights and with the side flanges of the base. For holding these hinged braces in their extended supporting relation, slide rings 40 are shown, which as will be clear in Fig. 1, may be slid backwardly or upwardly to release the extensions 41 of the lower brace arms and permit these braces to break at the center pivots 42.

The upper ends of the upright members are shown connected together in spaced relation by a rod 43, secured thereto by the cap nuts 44.

The apparatus may be used by simply grasping the cross rod 43 as a handle and walking the belt as a treadmill. More interest and exercise are attained however by the use of spring ten-

sioned pull cords carrying hand grips or a body encircling belt.

In Figs. 1 and 3, such pull cords are shown at 45, passing over pulleys 46, journaled on end portions of the handle bar 43, and extending downwardly and thence upwardly about pulleys 47, journaled on end portions of the lower stay rod 12 and attached to springs 48, having hooks 49, which may be caught in different openings 50, in the uprights.

An abdominal belt 51, may be hooked or otherwise detachably secured to the ends of the spring tensioned pull cords, or individual hand grips such as shown at 52, may be caught in rings 53, on the cords, or other body engaging or handle members may be connected with such cords.

In the use of the abdominal belt, it is particularly desirable that the pull against the abdomen be in an upward direction. Accordingly, the uprights should be high enough to give this upward lift to the abdominal organs. For this purpose, the uprights may be made vertically adjustable as by having the slideable sections 54, at the upper ends of the same, which can be secured at the proper height to give this desired effect as by the thumb nuts 55, on bolts 56, which extend through the slots 57, in the adjustable end sections.

To prevent cramping of the pulleys 46 and 47 at the upper and lower ends of the uprights, the latter are shown as formed with the doubled back or return bent portions 58, 59, forming pulley receiving yokes, which are prevented from collapse by the angularly bent ends 60, 61, in abutment with the sides of the uprights.

Constructed as described, the apparatus while relatively light, is rugged and strong, and can be produced and sold at relatively low cost. When the slide rings 40 are slipped back, the uprights can be folded down over the base, as indicated in Fig. 2, so as to occupy but small space, in which condition it may be stored in a closet or the like. The apparatus may be as easily unfolded and set up for use. In the inclined relation Fig. 1, agreeable and helpful exercise may be had by an easy walking motion and this may be made as strenuous or as mild as the individual desires. The uplifting effect on the abdomen may be varied by changing the connections of the springs with the uprights and by raising or lowering the upper pulley supporting sections of the uprights. By folding under the supporting legs 17, the platform may be brought down to the substantially horizontal position. In this relation it serves as a standing platform for an operator using the pull cords in the familiar weight lifting exercises. The substantially flat supporting plate with its downwardly curved ends provides the necessary friction as well as the entire support for the endless tread band, eliminating the need for any rollers, slats or the like, such as heretofore considered necessary in apparatus of this character. The elimination of rollers for the belt also makes the device entirely safe for either very young or very old or feeble persons to use. The belt is guided in its travel between the smooth inner faces of the legs 17 and these, as indicated in Fig. 7, are rigidly braced and coupled together by a tie rod indicated at 62. The end portions of the downwardly bent edge flanges of the base plate cover the downwardly curved end parts of said base plate and the end stays 12 and 14 extend within the curled under portions as shown

in Fig. 1, so that the parts are well secured together and the nuts may be set up as tightly as desired without collapsing the edge flanges.

The tie rod 62, connecting the legs 23 confines and supports the lower run of the belt in the folded condition indicated in Fig. 6. In either the inclined or the horizontal positions, the apparatus may be used by lying on the back and grasping the spring tensioned handles 52, and working the legs, using the upper cross bar 43, if desired, as a foot rest or pressure bar. The springs 48 may be interposed in the inside runs of the cords 45, that is, in the lengths extending between the upper pulleys 46 and the lower pulleys 47. The term "Hiker" has been applied to the machine as a trade-mark. The inwardly bent yokes at the upper and lower ends of the uprights serve as housings and guides for the pulleys and also as guides for the cords running over the pulleys. These yokes also act as guards for protecting the hands from the pulleys. The spaced legs for the upper end of the platform may act as guides for the lower run of the belt in the folded as well as in the supporting position as will be clear from Figs. 6 and 7.

25

What is claimed is:

1. Exercising apparatus of the treadmill type, comprising a substantially flat supporting plate having downwardly rounded ends and an endless tread band extending over and entirely supported and frictioned by said supporting plate and downwardly curved ends of the same.

30

2. Exercising apparatus of the treadmill type, comprising a substantially flat supporting plate having downwardly rounded ends and an endless tread band extending over and entirely supported and frictioned by said supporting plate and downwardly curved ends of the same, legs for positioning said supporting plate in an inclined relation, said legs being foldable to sustain the supporting plate in substantially horizontal relation, an upright connected with the supporting plate and pull means carried by said upright and usable in either the inclined or substantially horizontal positions of the supporting plate.

35

3. Exercising apparatus of the treadmill type, comprising a substantially flat supporting plate having downwardly rounded ends, an endless tread band extending over and entirely supported and frictioned by said supporting plate and downwardly curved ends of the same, said supporting plate having downturned edge flanges covering the edges of the downwardly curved end portions of the plate.

55

4. Exercising apparatus of the treadmill type, comprising a substantially flat supporting plate having downwardly rounded ends, an endless tread band extending over and entirely supported and frictioned by said supporting plate and downwardly curved ends of the same, said supporting plate having downturned edge flanges covering the edges of the downwardly curved end portions of the plate and stays connecting said downturned edge flanges of the supporting plate.

60

5. Exercising apparatus of the treadmill type, comprising a substantially flat supporting plate having downwardly rounded ends, an endless tread band extending over and entirely supported and frictioned by said supporting plate and downwardly curved ends of the same, said supporting plate having downturned edge flanges covering the edges of the downwardly curved end portions of the plate, stays connecting said downturned edge flanges of the supporting plate and

70

75

- a foldable upright pivotally supported on one of said cross stays.
6. Exercising apparatus, comprising a sheet metal supporting plate having downturned edge flanges and downwardly curved ends curled in between the ends of said edge flanges, an endless tread belt extending over said supporting plate and downwardly curved end plates and means for supporting said plate in position for operation of said tread belt.
7. Exercising apparatus, comprising a platform, supporting feet at one end of said platform shiftable to support said platform in either inclined or substantially horizontal relation, an endless tread belt extending over said platform, an upright at one end of said platform and spring tensioned pull mechanism carried by said upright and operable in either the inclined or the horizontal positions of the platform.
8. Exercising apparatus, comprising an inclined treadmill surface, a support positioned above the waistline of a person on said treadmill surface and an abdominal belt elastically connected with said support and thereby adapted to resiliently support and lift the abdominal region of a person on said inclined treadmill surface.
9. Exercising apparatus, comprising an inclined treadmill surface, an upright support at the lower end of said inclined treadmill surface, resilient connections with said support and means interchangeably engageable with said resilient connections engageable by a person on the treadmill surface.
10. Exercising apparatus, comprising a supporting platform having a top portion and downturned reinforcing side flanges, a treadmill surface riding over said top portion of said platform between said side flanges, said top portion having downwardly rolled parts at the ends of the same for said over-riding treadmill surface, cross stays between the end and intermediate portions of said side flanges within said downwardly rolled parts, an upright hingedly mounted on the cross stay at one end of said platform, braces for said upright hingedly mounted on the intermediate cross stay and exercising means resiliently connected with said upright and extensible over said treadmill surface.
11. Exercising apparatus, comprising a mov-
- able treadmill surface, an upright associated therewith, pulleys at the upper and lower ends of said upright, exercising cord connections extending about said pulleys and resilient means interposed in said cord connections.
12. Exercising apparatus, comprising in combination with a treadmill platform uprights associated therewith and having doubled end portions, pulleys located in said doubled end portions in the uprights and exercising cords extending about said thus mounted pulleys.
13. Exercising apparatus, comprising in combination with a treadmill platform, uprights associated therewith having adjustable sections vertically shiftable to a position above the waistline of a person on the treadmill platform and exercising cords carried by and leading from the upper end of said vertically adjustable sections and a body encircling belt connected with said cords to apply supporting pressure to the abdominal region of a person using the apparatus.
14. Exercising apparatus, comprising a treadmill platform, an upright at one end of said platform, exercising connections carried by said upright and hinged feet hinged to the opposite end portion of said treadmill platform foldable from an upright relation supporting the platform in inclined position to a lowered position supporting the platform in substantially horizontal relation.
15. Exercising apparatus, comprising a platform, a treadmill belt extending thereabout and a foldable support at one end of the platform including a cross stay positioned beneath the lower run of the belt to engage and support the belt in the folded position of the same.
16. Exercising apparatus, comprising a platform, spaced legs supporting one end of said platform and foldable into position beneath the same and a treadmill belt extending about the platform and guided between said legs in both the folded and the supporting positions of the legs.
17. In exercising apparatus, a treadmill platform and supporting legs for the same flanged in box form, said legs being hingedly connected with the platform in position with the upper flanges of said legs to engage beneath and support the platform and the bottom and side flanges to form end and side supports for the platform.

FRANK O'NEILL, JR. 50
